UNITED STATES PATENT OFFICE.

FREDERICK W. SCHNEIDER, OF BALTIMORE, MARYLAND, ASSIGNOR TO PITTSBURGH PLATE GLASS COMPANY, A CORPORATION OF PENNSYLVANIA.

PAINT GUN.

Application filed April 10, 1925. Serial No. 22,068.

The invention relates to pneumatic paint guns or brushes, and has for its principal objects; the provision of a construction having improved means for regulating the air supply in producing a flat spray and in shifting back and forth between a round and a flat spray; the provision of an improved nozzle construction whereby the removal and replacement of the nozzle tube is made more convenient, and whereby a tight joint is insured between the nozzle tube and body of the gun in which it is mounted; and the provision of an improved arrangement for mounting the trigger which operates the air and paint valves. One embodiment of the invention is illustrated in the accompanying drawings wherein:

Figure 1 is a plan view. Fig. 2 is a side elevation. Fig. 3 is a section on the line 20 III—III of Fig. 4. And Fig. 4 is a section on the lines IV—IV of Fig. 3.

Referring to the drawings, 1 is the body portion of the gun provided with a handle 2 and the head 3. Also with a hook 4 by means of which the device may be hung up. A connection 5 is provided, to which the receptacle containing the paint to be applied is attached. The paint from the receptacle is conducted to the nozzle tube 6 through the passage 7. Extending longitudinally of the body portion is a main air supply passage 8 to which air is supplied through the passages 9 and 10, the latter terminating at its lower end in the connection 11, to which a supply pipe is connected in the usual way.

The flow of air to the passage 8 from the passage 10 is controlled by means of the valve 12 held in closed position by means of the spring 13, the latter abutting at its rear end 40 against the nut 14. The flow of paint through the nozzle tube 6 is controlled by means of the needle valve 15 having a rearwardly extending stem 16 extending through the packing nut 17. The valve is normally held closed by means of the spring 18 which engages the nut 19 at its rear end. Both the air valve 12 and the paint valve 15 are operated from the trigger 20, which has its upper portion in the form of a yoke which straddles the body portion and is pivoted upon the pin 21. This pin 21 is held in position by means of the set screw 22 and when it is desired to remove the trigger, this is easily done by loosening the set screw 22 and pushing the pin 21 out endwise. The yoke

portion of the trigger has pivoted to it at 23 a second rearwardly extending yoke 24 which straddles the body portion and has its rear end fitting over the threaded rear end of the paint valve stem 16. The end of the 60 yoke member 24 is slotted as indicated at 25 and this portion of the member is clamped between the nuts 26 and 27. When it is desired to release the yoke member 24 from the valve stem 16, all that is necessary is to 65 loosen the nut 27, after which the yoke member can be moved downward and out of the way. The two nuts 26 and 27 permit of the longitudinal adjustment of the valve stem 16. 70

Fitting over the end of the nozzle tube 6 is a nozzle disc 28 which has its inner face coned, as indicated at 29 to fit a correspondingly coned or tapered surface on the forward end of the tube 6. The rear portion of 75 the tube 6 is also coned or tapered as indicated at 30 so as to fit into a correspondingly tapered seat in the head 3. The disc 28 is threaded into the head as indicated at 31, so that when this disc is screwed in tightly, it 80 forces the tube 6 into its tapered seat 30, thus making a tight joint between the head and the tube, while a correspondingly tight joint is secured between the disc and the tube at the tapered surface 29. This arrangement 85 assures against any leakage of paint past the nozzle tube and leaves this tube free to be removed without difficulty when the disc 28 is unscrewed. The disc 28 is provided with an opening 32 surrounding the outer end of 90 the nozzle tube, and air is supplied to this space through the passages 33. These passages communicate with the space 34 which in turn communicates with a branch passage 35 communicating with the end of the main 95 air passage 8 as indicated in Fig. 3. The disc 28 has a relatively loose threaded fit at 31, so that when the disc is screwed into position as illustrated in Fig. 3, it can center itself upon the tapered forward end of the 100 nozzle tube 6. The flow of air from the passage 8 to the passage 35 is throttled and controlled by means of the screw 36. The forward end of the head 3 is tapered or coned, as indicated at 37 and upon this tapered portion is mounted the cap 38 which carries the pair of supplemental discharge passages 39 and 40 for producing a flat spray. This cap is held in position by means of the nut 41. It is provided with a pair of rear- 105 110

wardly extending passages 42 and 43 (Fig. 4) which communicate at their rear ends with a groove 44, such groove being formed between the contacting surfaces of the head 5 and the cap and being preferably located in the cap. This groove is supplied with air through the second branch passage 45 (Fig. 3), which communicates at its rear end with the main passage 8, the flow of air being 10 regulated or entirely cut off when a round spray is desired by means of the screw 46. By adjusting this screw, the character of the flat spray may be adjusted to meet varying requirements.

15 What I claim is:

1. In combination in a paint gun, a body portion having air and paint valves and a transverse perforation, a trigger arranged to operate the valves and having a yoke 20 ranged to straddle the body and having perforations in the ends of the yoke adapted to align with said transverse perforation through the body, a pin extending through said perforations in the body and the yoke 25 and acting as a pivot for the trigger, and a set screw in the body extending transversely of the pin and engaging the pin and holding it against endwise movement, the said pin being mounted so as to be freely movable 30 endwise when released by said set screw.
2. In combination in a paint gun, a body provided with a head having a longitudinal supply passage terminating in a conical seat at its outer end, a nozzle tube having its rear 35 end tapered to fit said conical seat and also having its forward end reversely tapered, and a nozzle disc open at its center and having threaded engagement with the head and

provided with a tapering seat adapted to fit the taper upon the outer end of the nozzle 40 tube.

3. In combination in a paint gun, a body provided with a head having a longitudinal supply passage terminating in a conical seat at its outer end, a nozzle tube having its rear 45 end tapered to fit said conical seat and also having its forward end reversely tapered, and a nozzle disc open at its center and having threaded engagement with the head and provided with a tapering seat adapted to fit 50 the taper upon the outer end of the nozzle tube, the fit between the threads of the disc and head being relatively loose so that the disc is free to center itself upon the nozzle tube.

4. In combination in a paint gun, a body provided with a head having a longitudinal paint supply passage terminating in a conical seat at its outer end and with an air supply passage, a nozzle tube having its rear end tapered to fit said conical seat and also having its forward end reversely tapered, and a nozzle disc open at its center threaded into the outer end of the head and provided with a tapering seat 60 adapted to fit the taper on the outer end of the nozzle tube and with a passage leading from its rear end to said open center, the rear end of the disc being spaced away from the head to provide an annular space, and said air supply passage in the body terminating at said space.

In testimony whereof, I have hereunto subscribed my name this 30 day of March, 1925.

FREDERICK W. SCHNEIDER.
